UNITED STATES PATENT OFFICE.

FRANCIS M. RITES, OF ITHACA, NEW YORK.

VALVE-GEAR FOR EXPLOSIVE AND INTERNAL-COMBUSTION ENGINES.

No. 888,037.

Specification of Letters Patent.

Patented May 19, 1908.

Application filed May 8, 1905. Serial No. 259,259.

To all whom it may concern:

Be it known that I, FRANCIS M. RITES, a citizen of the United States, residing at Ithaca, in the county of Tompkins and State 5 of New York, have invented certain new and useful Improvements in Valve-Gear for Explosive and Internal-Combustion Engines; and I do hereby declare the following to be a full, clear, and exact description of the 10 same, such as will enable others skilled in the art to which it appertains to make and use the same.

My invention relates to improvements in automatic regulating devices for internal 15 combustion engines, and involves a modification of the invention set forth in U. S. Letters Patent No. 741,796, dated October 20, 1903, and in my application for Letters Patent filed January 28, 1904, Sr. No. 20 188,170.

The valve gear herein described is particularly adapted for operating valves of the poppet type which normally are held closed by a suitable spring or equivalent device, and 25 my improved valve gear is arranged to open such valves positively, and likewise to effect regulation of the speed of the engine by varying the point of valve closure or cut off.

The improved valve gear herein described 30 embodies means for tripping the valve-operating device at a predetermined point in the stroke, permitting the valve to close independently of the action of the valve gear.

The objects of my invention are, to improve 35 the valve gear and governing mechanism of explosion or internal combustion engines of the class described, to open positively poppet or other valves which normally are held closed by springs or equivalent 40 means, to regulate the speed of the engine by varying the point of valve closure, to permit the point of valve closure to be determined, even in large engines, by a delicate governor, to permit the valve to close independently 45 of the valve gear, and to make the valve gear as simple, compact and effective as possible.

I will now proceed to describe my invention with reference to the accompanying 50 drawings, in which one form of valve gear embodying my invention applied to a four-cycle engine is illustrated, and will then point out the novel features in claims.

In the said drawings:— Figure 1 shows an elevation and partial section of a vertical engine fitted with my improved valve and regulating mechanism; Fig. 2 is a detail side view of a portion of this mechanism, showing particularly the tripping device; Fig. 3 is a detail top view of a portion of the mechanism shown in Fig. 2.

Referring first to Fig. 1, the engine therein shown comprises a working cylinder 1, a combined base and crank chamber 2, a crank shaft 3, and a valve chamber 4 at the upper 55 end of the cylinder 1. The cylinder may have the usual piston and piston rod for driving the crank shaft.

Upon the crank shaft 3, there is a fly-wheel 5, carrying a fly-wheel governor 6 of 60 the shifting eccentric type, the pin eccentric 7 of which is arranged to be swung across the end of the crank shaft 3, by motion of the governor weight.

Upon the crank shaft 3, there is a pinion 75 8, intermeshing with a gear 9, carrying a crank pin 10. The ratio of gears 8 and 9 in a four-cycle engine of the usual type is two to one, gear 9 revolving at one-half the speed of gear 8.

The admission valve 11 shown, is of the poppet type, its valve stem 12 working within suitable bearings, and being surrounded by a spring 13, tending to hold the valve closed. This valve is opened positively at 85 suitable times, and permitted to close automatically, by tripping valve-operating mechanism particularly illustrated in Figs. 2 and 3. This mechanism comprises an arm 14 pivoted to some suitable stationary portion 90 of the engine, connected by a rod 15 to the crank pin 10 of gear 9. The outer end of this arm 14 carries a hook 16, adapted to engage the end of the valve stem 12. This hook 16 is pivoted to 14, and is provided with a cam-shaped portion 17. A trip cam 18 having the form of a bell crank lever, is also pivoted on 14, and at times engages the cam portion 17 of hook 16. This trip cam 18 is connected by eccentric rod 19 to the governor eccentric 95 7. A spring 20 tends to hold the hook in engagement with the end of the valve stem.

The operation of this valve gear is as follows: Since arm 14 is caused to reciprocate 100 by a crank driven at one-half the speed of

the engine, the hook 16 engages the stem 12 to open the valve 11 only at the beginning of each admission stroke of the engine. The cam 18 is vibrated by the governor eccentric, and at a variable point in the admission stroke, dependent upon the position of the eccentric as determined by the governor, the cam 18 presses on the hook 16 in such manner as to trip the same, releasing the valve 11, and permitting the latter to close. These operations are repeated during each admission stroke, the valve being tripped automatically in such stroke at the point predetermined by the adjustment of the governor.

15 Governor eccentric 7 and crank pin 10 constitute valve actuating devices driven at different speeds, for operating and controlling the operation of the valve gear.

It will be seen that by this mechanism the 20 valve is opened positively, and that regulation is caused by varying the point of cutoff; and that the mechanism of the valve gear is very simple and direct acting, and contains very few joints. Furthermore, the work required of the governor is very slight, being merely that required to trip the hook 16. This valve gear is, therefore, particularly suitable for large engines, since it permits an engine of practically any size to be governed 25 by a small, compact and relatively inexpensive governor.

In my aforesaid application, Sr. No. 188,170, I have claimed, in a valve gear, two 30 valve actuating devices driven at different speeds, and valve operating means operated thereby, comprising a reciprocating member having a fixed support, which member is connected to the slower moving of the actuating devices, and another member mounted 35 upon such reciprocating member, connected to the other of said actuating devices, and arranged to be reciprocated thereby. Therefore, such invention is not claimed herein.

In the use of poppet admission valves in 40 internal combustion engines, it is usually preferred to have such valves closed by action of a spring, and to have such spring act at all times to hold the valve closed, except during the admission period; and it is also 45 usually preferred to have said valve opened positively by the valve gear for admission. The valve gear above described fulfills all these requirements.

It is obvious that my invention is susceptible 50 of many modifications and variations in form, construction, and arrangement of the parts without departing from the basic principle thereof.

I do not limit myself to the particular 60 details of construction and arrangement illustrated and described, nor to the particular type of valve shown nor to the specific construction of tripping mechanism illustrated and described.

65 While in the drawings I have shown a

spring for holding the valve closed, and I have referred to such spring in the claims, it is obvious that other valve closing devices, equivalent to the spring, such for example as weights or vacuum pots, may be substituted for the spring, and such substitution I regard as within the invention and the claims.

The fly-wheel governor illustrated is of a type in common use, heretofore invented 75 and patented by me, and comprises the single weight 6, pivoted at 21 to the fly-wheel, and having combined centrifugal and inertia action. To the weight and to the fly-wheel are connected opposite ends of the governor 80 spring, 22. With increase of rotative speed, this weight tends to swing outward against the pull of spring 22, and so to move eccentric 7 nearer the center of rotation, thereby causing hook 16 to trip and release the valve 85 stem 12 earlier in the stroke.

What I claim is:—

1. In an internal combustion engine, the combination with an engine cylinder and an automatically closed valve therefor, of valve 90 gear comprising a valve operating arm, means for reciprocating the same, a catch carried thereby for engaging said valve, a tripping cam mounted on said arm, and means for automatically operating said cam 95 to trip said catch.

2. In an internal combustion engine, the combination with an engine cylinder and an automatically closed valve therefor, of valve 100 gear comprising a valve operating arm, means for reciprocating the same, a catch carried thereby for engaging said valve, a tripping cam mounted on said arm, an automatic speed governor, and means operated thereby for operating said catch. 105

3. In an internal combustion engine, the combination with an engine cylinder and an automatically closed valve therefor, of valve 110 gear comprising a valve operating arm, means for reciprocating the same, a catch carried thereby for engaging said valve, a tripping cam mounted on said arm, a shifting eccentric governor, and means connecting the eccentric thereof to said cam.

4. In an internal combustion engine, the 115 combination with an engine cylinder and an automatically closed valve therefor, of valve gear comprising a valve actuating arm, means for reciprocating the same, a hook carried thereby and adapted to engage the 120 valve, a tripping cam therefor mounted eccentrically on said arm and arranged to engage said hook to operate the same, and means for vibrating said cam.

5. In an internal combustion engine, the 125 combination with an engine cylinder and an automatically closed valve therefor, of valve gear comprising a valve actuating arm, means for reciprocating the same, a hook carried thereby and adapted to engage the 130

valve, a tripping cam therefor mounted eccentrically on said arm and arranged to engage said hook to operate the same, an automatic speed governor, and means operated thereby for vibrating said cam.

6. In an internal combustion engine, the combination with an engine cylinder and an automatically closed valve therefor, of valve gear comprising two valve actuating devices 10 driven at different speeds, means operated by one of them for opening said valve the other of said actuating devices being an eccentric, and automatic tripping means operated by said eccentric for releasing the valve.

15 7. In an internal combustion engine, the combination with an engine cylinder and an automatically closed valve therefor, of valve gear comprising two valve actuating devices driven at different speeds, means operated 20 by one of them for opening said valve the other of said actuating devices being a shifting eccentric, automatic tripping means operated by said eccentric for releasing the valve, and automatic means for adjusting 25 said eccentric.

8. In an internal combustion engine, the combination with an engine cylinder, and an automatically closed valve therefor, of valve gear comprising two valve actuating devices 30 driven at different speeds, means operated by the slower of said devices for opening said valve, the other of said actuating devices being an eccentric, and automatic tripping means operated by said eccentric for 35 releasing the valve.

9. In an internal combustion engine, the combination with an engine cylinder, and an automatically closed valve therefor, of valve gear comprising two valve actuating devices 40 driven at different speeds, means operated by the slower of said devices for opening said valve, automatic tripping means operated by the faster of said valve actuating devices for releasing the valve, and an automatic speed governor controlling the action 45 of said tripping means.

10. In an internal combustion engine, the combination with an engine cylinder and an automatically closed valve therefor, of valve 50 gear comprising a valve operating member adapted to open said valve, tripping means for releasing the valve, two valve actuating devices driven at different speeds, one operating said valve operating member, the other 55 operating said tripping means, and a fly wheel governor adjusting the action of said last mentioned valve actuating device.

11. In an internal combustion engine, the combination with an engine cylinder and an 60 automatically closed valve therefor, of valve gear comprising a valve operating member adapted to open said valve, tripping means for releasing the valve, two valve actuating devices driven at different speeds, the slower

moving operating said valve operating member, the other operating said tripping means, and a fly wheel governor adjusting the action of the said faster valve actuating device.

12. In an internal combustion engine, the combination with an engine cylinder, and an 70 automatically closed valve therefor, of valve gear comprising two valve actuating devices driven at different speeds, a valve operating arm driven by one of said actuating devices, a catch carried thereby for engaging said 75 valve, and a tripping cam carried by said arm and operated by the other actuating device, for releasing said valve.

13. In an internal combustion engine, the combination with an engine cylinder, and an 80 automatically closed valve therefor, of valve gear comprising two valve actuating devices driven at different speeds, a valve operating arm driven by the slower of said devices, a catch carried thereby for engaging said valve, 85 and a tripping cam carried by said arm and operated by the other actuating device, for releasing said valve.

14. In an internal combustion engine, the combination with an engine cylinder, and an 90 automatically closed valve therefor, of valve gear comprising two valve actuating devices driven at different speeds, a valve operating arm driven by the slower of said devices, a catch carried thereby for engaging said valve, 95 a tripping cam carried by said arm and operated by the other actuating device, for releasing said valve, and an automatic governor controlling the action of said last named actuating device.

15. In an internal combustion engine, the combination with an engine cylinder and an automatically closed valve therefor, of valve gear comprising a governor, reducing gearing driven from the crank shaft, a valve operating 105 arm vibrated thereby, a catch carried by said arm and arranged to engage said valve, and a tripping cam for said catch, carried by said arm and controlled by said governor.

16. In an internal combustion engine, the 110 combination with an engine cylinder, of valve gear comprising a shifting eccentric governor driven at the speed of the crank shaft, reducing gearing driven from the crank shaft, a valve operating arm vibrated 115 thereby, a catch carried by said arm and arranged to engage said valve, and tripping means for said catch, controlled by said shifting eccentric governor.

17. In an internal combustion engine, the 120 combination with an engine cylinder, and an automatically closed valve therefor, of valve gear comprising tripping mechanism, a valve operating device moving at half the speed of the engine, and an automatic speed governor 125 comprising a revoluble adjustable member moving at the speed of the engine and arranged to operate said tripping mech-

anism and automatic means for adjusting said member.

18. In an internal combustion engine, the combination with an engine cylinder, and
5 valve gear therefor comprising reducing gearing driven by the engine, of means operated thereby for opening a valve comprising tripping means, and a shifting eccentric governor

driven at the speed of the engine and arranged to operate said tripping means. 10

In testimony whereof I affix my signature, in the presence of two witnesses.
